UNITED STATES PATENT OFFICE.

ROSS C. BEEKMAN, OF KANSAS CITY, KANSAS.

SANITARY POWER-DRIVEN CARPET BEATER.

Application filed November 6, 1920. Serial No. 422,345.

To all whom it may concern:

Be it known that I, Ross C. BEEKMAN, a citizen of the United States, residing at Kansas City, in the county of Wyandotte 5 and State of Kansas, have invented certain new and useful Improvements in Sanitary Power-Driven Carpet Beaters, of which the following is a specification.

My invention relates to a new and useful sanitary, power-driven carpet beater, and one object of the invention is to provide a machine of this character which can be operated by power, such as a gasoline engine, electric motor, or the like, thus 15 performing a quicker and more thorough piece of work.

Another object is to provide a carpet beater in which the dust beaten from a carpet or rug may be collected and thus 20 prevent the same from flying about in the air as is now the case when carpets are beaten in the ordinary manner.

The machine, generally speaking, consists of oppositely-disposed rolls over which the 25 carpet is fed forward and backward, said rolls having a beater arrangement therebetween through which the carpet must pass as it moves back and forth over the above-mentioned rolls. The machine further consists of means for collecting the dust and 30 discharging it into a suitable container or dust collector, from which it may be blown by a fan into a dust-proof box, sack, or the like.

With the above and other objects in view, reference will now be had to the accompanying drawings, in which:

Fig. 1 is a longitudinal elevation of the carpet beater.

Fig. 2 is a longitudinal section of the machine turned around from the position disclosed on Fig. 1.

Fig. 3 is a top or plan view of the machine.

Fig. 4 is a longitudinal elevation of a fastening device for securing the ends of the carpet upon the feed rolls of the machine.

Fig. 5 is a cross section of said fastening device, in position upon the carpet.

Fig. 6 is a cross section of the entire machine.

Fig. 7 is a longitudinal elevation showing the mechanism for rotating the feed rolls and reversing them.

Fig. 8 is a fragmentary plan view of the means for securing the carpet to the feed

rolls, and disclosing the manner in which said fastening means reverses the feed rolls.

Referring now more particularly to the machine, the carpet beater, as a whole, is supported upon a frame consisting of corner posts 2, connected by longitudinal members 4 and cross members 6. Oblique braces 8 are secured to the legs and the cross members 4 and 6, and longitudinal braces 10 are secured to the opposite legs 2. Upright, 60 central brace members 11 are secured to opposite sides of the frame, said braces being connected at their tops by a cross beam 15 which adds strength and rigidity to the 70 frame and serves as a support for a large part of the mechanism.

In order to feed the carpet backward and forward while being beaten or cleaned, I provide two oppositely-disposed rolls 14, 75 said rolls may be of any suitable construction. The rolls are fixedly mounted upon shafts 22 which are journaled in suitable bearings, in the frame members 4.

One end of each shaft 22 has a ratchet 80 wheel 24 fixedly mounted thereon, said wheel having a cooperating pawl 26, mounted on pins 27 secured between small members 29 and depending levers 31, for a purpose which will hereinafter appear.

The opposite ends of the shafts 22 are provided with ratchet wheels 30 and pawls 32 to prevent their respective rolls from rotating backwardly when the carpet is being pulled forwardly by one of said rolls. 90 Said pawls 32 are pivotally mounted on pins 36 secured in a block 38, a brace 40 being provided to firmly hold said block in place.

That part of the machine which performs the beating or cleaning operation consists of two distinct parts, viz: a beater bed and a series of beater arms which work in conjunction with said beater bed. Referring to the beater bed in detail, the same may be said to consist of a frame having transverse members 50 and end members 52, said frame being mounted on oppositely disposed pivots 58 journaled in the side members 4 of the frame, so that the entire frame may be swung up when desired in order to repair or remove any obstruction from the dust collector which lies directly under the beater bed, as will hereinafter appear. A coarse wire netting 60 is fitted over the 100 beater bed frame, being secured by screws or other suitable means. Upon said screen 105

- or netting 60 is mounted a series of springs 61 secured thereto at their lower ends by clips or other means, and at their upper ends by cables 63 running over the tops of said springs and secured thereto in any suitable manner. The ends of said wires or cables are firmly secured to the cross members 50 of the beater bed frame by screws 64 or other suitable means. It will thus be seen that the whole furnishes an open and resilient beater bed through which the dust may sift, as it is beaten from a carpet, down into a dust proof receiver or dust collector, as will hereinafter appear.
- 15 Referring to the beater arms which perform the actual beating or cleaning operation on the carpet, the same consist of a series of arms consisting of wire or other suitable material. Said beater arms are secured at their rear ends between an L-beam 72 and a longitudinal member 74 firmly secured to said L-beam by bolts 76 or other means. Both the L-beam and the member 74 are mounted upon a shaft 80 journaled in the upright frame members 11.
- 20 One end of the shaft 80 extends outwardly and has a crank 82 to which is secured a link 84, said link being secured at its lower end to a second crank 86. The crank 86 forms part of a shaft 88 extending across the entire machine and journaled in the upright members 11. A pulley 90 is fixedly mounted on the opposite end of the shaft 88 to which a belt 92 is secured, over which power may be transmitted from a gasoline engine, electric motor, or other suitable source, for operating the machine.
- 25 As the dust is beaten from a carpet, it passes downwardly through the open frame work of the beater bed into a trough-like dust collector 100, made of any dust-proof material, as cloth, tin, wood, or the like. Said dust collector is substantially U-shape in cross section and is secured at one upper margin to a beam 102, secured at its ends to the longitudinal members 4. The opposite margin of the dust collector is secured to the back member 50 of the beater bed. It will thus be seen that the upper portion of the dust collector is left open in order that dust and dirt may settle therein as it falls from the beater bed. However, no dust can escape from the dust collector as the former is at all times covered by the carpet A, or its fastening means 129.
- 30 In order to blow or discharge the dust from the dust collector, I provide a fan 110 which operates continuously while the machine is in motion. Said fan is journaled in a depending bracket 11 and is provided with a pulley over which a belt 112 operates to rotate said fan. Said fan sucks air in at the open end of the dust collector, which latter is covered by a screen, and thus creates a strong draft through the dust collector
- 35 which carries the dust to an opening 114 through which it is discharged into any suitable container. If desired the discharge opening may be made in the side of the dust collector and several sections of stove pipe 70 or the like (not shown) connected thereto to discharge the dust out through the end of the machine into a suitable container.
- 40 In order to more fully remove all dirt from the carpet, a powerful rotary brush 162 is employed journaled in the side members 4 and having a basin or trough-like pan 163 thereunder, into which the lower end of the brush dips, said trough being filled with a washing fluid, which is renewed 75 from time to time by a supply tank at a distance from the machine (not shown) the dirty water being discharged from the trough as new water is supplied.
- 45 A second rotary brush 116 is also supplied being mounted upon a shaft 118 journaled in the main frame members 4. Shaft 118 has a pulley 120 which receives power through a belt 122 connected to the fan shaft 110.
- 50 To allow the extreme ends of the carpet A to move forwardly from their respective rolls, into position over the beater bed, I do not connect said carpet directly to the feed rolls but secure the same thereto through 90 the intermediacy of a holder consisting of a stout cloth strip such as canvas 129, said strip being secured to its respective roll in any manner, as by screws, etc. The opposite end of the strip 129 has a member for engaging the end of the carpet A, consisting of upper and lower longitudinal plates 138 and 136 respectively, held together by screws 140, between which the ends of the carpet A can be firmly clamped. Two of said fastening members are provided, one to secure each end of the carpet to its respective holder. The solid cloth holder 129 also prevents any dust from escaping from the dust collector should the carpet run a slight distance beyond the edge of the beater bed, which action would leave a portion of the dust collector open if the carpet were merely secured by open strips.
- 55 The main feed rolls receive rotary motion 105 through the ratchet wheels 24 through the intermediacy of the pawls 26. Said pawls in turn receive their motion from the levers 31 which extend downwardly and are connected to links 125, which are connected to the central crank 88 driven by the main shaft 81. In order to reverse the motion of the ratchets and their respective rolls and thus alternately pull the carpet back and forth over the beater bed, two push-rods 142 are provided, being connected at their inner ends by a hinge 144. Two pairs of rods 142 are provided, one pair being on each side of the main frame. Said push-rods are slidably mounted in brackets 143, and are provided 110
- 60
- 65
- 70
- 75

with adjustable striking arms 146 and 148, respectively, against which the fastening members 136 and 138 for holding the carpet are adapted to alternately strike in their travel back and forth with said carpet. This action forces the push-rods one way or the other and through the intermediary of bell-crank 150 and lift rods 162, raises the two ratches on one roll and lowers those on the opposite roll, thereby reversing the motion of said rolls and causing the carpet to travel back and forth.

The operation of the machine, briefly stated, is as follows: When it is desired to clean a carpet or the like one end of said carpet is secured in position between one pair of the fastening plates 132 and 138 by securing it between said plates and tightening the nuts or screws 140, thus drawing said plates firmly together upon the edge of the carpet, after which the opposite end of the carpet is secured in a like manner to its respective fastening device. The feed rolls are then turned back far enough by hand to take up any slack in the carpet, after which the machine is set in motion by applying the power. As the belt 92 rotates its pulley 90 the latter drives the main shaft 81 and the crank 88 on the opposite end of said shaft 81. As said crank rotates it moves its links 86 back and forth which causes the levers 31 to swing back and forth, and through the intermediary of the pawls 26, impart a step-by-step rotary motion to the ratchet wheels 24 and their respective shafts and rollers 14. As before stated, only one roller 14 is kept in motion at a time, the opposite roll merely feeding the carpet forward as said carpet is pulled across the beater bed by the adjacent roller. Backward rotation of said roll 14 which happens to be pulling the carpet forward, is prevented by the pawl and ratchet on the opposite end of the roller. The pawls and ratchets on the idle roll are held in disengaged position until the carpet has approximately reached the edge of the beater bed, when its fastening member, which has also traveled forward with the carpet, strikes the striker arm 148 as shown in Figs. 7 and 8, which action through the intermediary of the push-rods 142, the bell cranks 150, and the lift rods 162, raises one set of pawls out of engagement with its respective roll, and lowers the pawls on the opposite roll, thus reversing the motion of the feed rolls and drawing the carpet back and forth over the beater bed. In the meantime, as the carpet A travels back and forth over the beater bed, the beater arms 48 are caused to swing rapidly up and down through the intermediary of their shaft 80 which is given a rapid oscil-

latory motion through the intermediary of its crank 82 and the link 84, which latter receives motion from the main power shaft 81, through the intermediary of the crank 88. As the dust is beaten from the carpet it sifts downwardly through the open frame work of the beater bed into the dust collector 100, from which the fan 110 blows it outwardly through the nozzle 114 into a container (not shown).

Having thus described my invention, what I claim and desire to secure by Letters Patent, is:

1. In a machine of the character described, two rolls around which a carpet is adapted to be wound, means for rotating said rolls, means for reversing the movement of said rolls; said reversing means being actuated by the travel of the carpet, a beater bed over which said carpet travels, beater arms to beat said carpet while a certain portion of the latter is over the beater bed.

2. In a machine of the character described, two rolls over which a carpet is adapted to travel, means for securing the carpet to said rolls in such manner as to allow its extreme ends to move forwardly a certain distance from the rolls, in order that all of said carpet may be cleaned, means in conjunction with said fastening means for reversing the travel of the carpet when its end has approximately reached the edge of the beater bed, and means for cleaning said carpet as it travels over the beater bed.

3. In a machine of the character described, rolls for moving a carpet in alternate directions, means for applying power to one of said rolls for the purpose of rotating the same while its opposite roll is allowed to run idle, means for removing the power actuating means from one roll and applying it to the companion roll, means on the carpet for controlling said power actuating and reversing means, substantially as described.

4. In a machine of the character described, rolls for moving a carpet in alternate directions, ratchet wheels on said rolls, pawls for engaging said ratchet wheels, means on the carpet and its fastening means for lifting one set of pawls out of engagement with its respective ratchet wheels and lowering the opposite set of pawls into engagement with its respective ratchet wheels, and means for beating said carpet as it is thus moved in alternate directions.

In testimony whereof I affix my signature, in the presence of two witnesses.

ROSS C. BEEKMAN.
